ATTORNEY.

UNITED STATES PATENT OFFICE.

LEONARD D. SOUBIER, OF TOLEDO, OHIO, ASSIGNOR TO THE LIBBEY-OWENS SHEET GLASS COMPANY, OF TOLEDO, OHIO, A CORPORATION OF OHIO.

SHEET-HEATING MEANS.

Application filed March 25, 1925. Serial No. 18,100.

The present invention relates to sheet glass apparatus, and has particular reference to means for heating a sheet of glass which is to be deflected from one plane to another.

An important object of the invention is to provide means for continuously drawing a sheet of glass from a source of molten glass, and includes means for deflecting the sheet from one plane to another.

A further object of the invention is to provide means for heating a sheet of glass which is being deflected from one plane to another by means of indirect heat, thus permitting a uniform treatment of the glass being acted upon.

Still another object is to provide apparatus of this nature wherein a sheet of glass is bent from one plane to another, and includes a chamber arranged in proximity to the point where the sheet is being bent, whereby heated air may be caused to pass and act upon the sheet sufficiently to soften the sheet to facilitate bending or deflecting thereof.

Other objects and advantages of the invention will become apparent during the course of the following description.

In the drawings wherein like numerals are employed to designate like parts throughout the same.

Fig. 1 is a vertical longitudinal section through a portion of the apparatus, and

Fig. 2 is a transverse vertical section therethrough.

This invention is particularly well-adapted for use in conjunction with the machine disclosed in the Colburn Patent 1,248,809, granted Dec. 4, 1917, wherein a sheet 5 is drawn from a pool of molten glass 6 contained in a draw-pot 7, which is supported upon the stools 8. The draw-pot 7 is in open communication with a tank furnace 9 by which means the meniscus or sheet source 10 is continuously replenished. Sheet edge engaging rolls 11 are provided to engage both sides of the sheet at its edges to retard the flow of glass into the said edges, whereby the sheet is held to width after it has been formed. Cover-titles 12 are provided

to protect the sheet from heat currents present in and around the machine. The sheet 5 is deflected over a so-called bending roll 13 so that the sheet may be passed in a horizontal plane over an idler roll 14, draw table 15, and through an annealing leir which is not shown.

It is customary in the actual use of the Colburn machine to apply an open flame to the sheet before and as it passes over the bending roll 13 to sufficiently soften the glass to permit of deflection without injury to the same. This is due to the fact that the sheet from the time it leaves the meniscus 10 until it reaches the bending roll 13 has set up or become so viscous that without the heating as by the open flame, the sheet may be injured or warped. The heating softens the glass just enough to enable it to be bent at right angles without serious damage. It will readily be understood however that it is almost impossible to apply an open gas flame directly to the sheet and have a heating action uniform throughout the entire width of the sheet. In view of the fact that the heating is not uniform, the sheet is not softened throughout its entire width to the same extent, and it is believed that this unequal heating of the sheet has a tendency to create waves and other defects in the sheet.

An aim of the present invention is to provide a heating chamber in proximity to the bending roll 13 so that the sheet may be heated indirectly by a uniform blast of heated air. The chamber 16 is provided with a centrally adjustable gate or valve member 17 which is shown as being diagrammatically supported by the cable 18 by which means it may be adjusted through the slot 19 formed in the top 20 of the construction. By raising and lowering the gate 17, the lower preferably curved end 21 will be moved to and from the sheet passing over the bending roll 13. The gate 17 in the chamber 16 creates channels 22 and 23, the channel 23 having in its upper end a flue 24 controlled by the damper 25. Suitable heating means which may be in the nature of a gas burner 26 are positioned within the flue or passage 22. The flue 24 will create a suf-

100

5 ficient draft to cause a circulation of the heated air from the passage 22 down around the curved end of the gate 17 and up through the passage 23. In passing around the end of the gate 17 the blasts of heated air will strike the sheet being passed over the bending roll and will soften the same sufficiently to permit a deflection of the sheet without injury. The blast of air will be substantially uniform in temperature throughout its entire width due to the circulation caused by the flue 23. In addition to heating the sheet uniformly, the flame and gases do not directly strike the sheet which is an advantage.

10 It is to be understood that the form of the invention herewith shown and described is to be taken as the preferred embodiment of the same, and that various changes in the shape, size and arrangement of parts may be resorted to without departing from the spirit of the invention or the scope of the subjoined claims.

15 Claims:

20 25 1. In sheet glass apparatus, means for drawing a sheet from a mass of molten glass, means for deflecting the sheet from one plane to another, means for heating a current of air, means for causing the heated air 30 to be directed downwardly upon the sheet as it is being deflected and then drawn upwardly away therefrom, and means for controlling the intensity of the heating action of said air on the sheet.

35 40 2. In sheet glass apparatus, means for drawing a sheet from a mass of molten glass, means for deflecting the sheet from one plane to another, a chamber above and in proximity to the point where the sheet is deflected, means for creating a current of air within the chamber and for passing the same downwardly across the sheet, and means for heating the said current.

45 50 3. In sheet glass apparatus, means for drawing a sheet from a mass of molten glass, means for deflecting the sheet from one plane to another, a heating chamber arranged above and in proximity to the sheet at the point where it is being deflected, means to create a downward and then upward circulation of air in the heated chamber, and means for controlling the action of the heated air on the sheet.

55 60 4. In sheet glass apparatus, means for drawing a sheet from a mass of molten glass, means for deflecting the sheet from one plane to another, a heating chamber arranged above and in proximity to the sheet at the point where it is being deflected, means to create a downward and then upward circulation of heated air in the heated chamber, and a damper for controlling the intensity of the action of said heated air on the sheet of glass.

65 5. In sheet glass apparatus, means for

70 drawing a sheet from a mass of molten glass, means for deflecting the sheet from one plane to another, a heating chamber arranged above and in proximity to the sheet at the point where it is being deflected, means to create a downward and then upward circulation of heated air in the heated chamber, a damper for controlling the intensity of the action of said heated air on the sheet of glass, and an outlet passage for 75 said heated air after it has acted on the said sheet of glass.

75 80 6. In sheet glass apparatus, means for drawing a sheet from a mass of molten glass, means for deflecting the sheet from one plane to another, a chamber arranged in proximity to the sheet at the point where it is being deflected, means for dividing the chamber into a plurality of passages, means for creating a current of air adapted to pass 85 from one passage to another, said current of air striking the sheet as it passes from one passage to another, and means for heating the air before it contacts with said sheet.

85 90 7. In sheet glass apparatus, means for drawing a sheet from a mass of molten glass, means for deflecting the sheet from one plane to another, a chamber arranged in proximity to the sheet at the point where it is being deflected, means for dividing the chamber into a plurality of passages, means for creating a current of air adapted to pass 95 from one passage to another, said current of air striking the sheet as it passes from one passage to another, and means for heating 100 the air before it contacts with said sheet, the means between said passages being adjustable.

90 105 8. In sheet glass apparatus, means for drawing a sheet from a mass of molten glass, means for deflecting the sheet from one plane to another, a chamber arranged in proximity to the sheet at the point where it is being deflected, means for dividing the chamber into a plurality of passages, means 110 for creating a current of air adapted to pass from one passage to another, said current of air striking the sheet as it passes from one passage to another, means for heating the air before it contacts with said sheet, and 115 means for controlling the intensity of the action of the heated air upon said sheet.

95 120 9. In sheet glass apparatus, means for drawing a sheet from a mass of molten glass, means for deflecting the sheet from one plane to another, a chamber arranged in proximity to the sheet at the point where it is being deflected, means for dividing the chamber into a plurality of passages, means 125 for creating a current of air adapted to pass from one passage to another, said current of air striking the sheet as it passes from one passage to another, and means for heating the air before it contacts with said sheet, the means between said passages being ad- 130

justable for controlling the intensity of the heated air upon said sheet.

10. In sheet glass apparatus, means for drawing a sheet from a mass of molten glass, means for deflecting the sheet from one plane to another, means for heating a current of air, and means for causing the heat-

ed air to be directed downwardly upon the sheet as it is being deflected and then drawn upwardly away therefrom.

Signed at Toledo, in the county of Lucas, and State of Ohio, this 23d day of March, 1925.

LEONARD D. SOUBIER.
